UNITED STATES PATENT OFFICE.

DAVID RHYS GRIFFITHS, OF LANGSIDE, GLASGOW, SCOTLAND.

FASTENING MEANS FOR SECURING FABRIC TO A BASE OF WOODWORK OR OTHER MATERIAL.

Application filed November 27, 1922. Serial No. 603,425.

To all whom it may concern:

Be it known that I, DAVID RHYS GRIFFITHS, a subject of the King of the United Kingdom of Great Britain and Ireland, and residing at Langside, Glasgow, Scotland, have invented a certain new and useful Improvement in Fastening Means for Securing Fabric to a Base of Woodwork or Other Material, of which the following is a specification.

This invention relates to fastening means for securing fabric to a base of woodwork or other rigid material of the type in which the fabric is passed around a locking strip which is inserted into a slot in the base and tilted in order to secure the fabric by its wedging action. The invention is concerned more particularly with fastening means for securing fabric blinds to blind rollers.

The object of the present invention is to provide an improved construction of such fastening means which will be simple and cheap to manufacture, easy to manoeuvre and efficient in action.

A feature of the invention is the provision of a spring or springs at the base of the slot nearer the unshouldered wall than the shouldered wall and adapted normally to urge the strip towards the shoulder.

The invention is shown as applied to a blind roller in the accompanying drawing in which Fig. 1 is a section showing the locking strip in operative position and Fig. 2 a section showing the strip partly inserted in the slot.

As shown, the base constituted by a blind roller 1 to which the fabric 2 is to be secured is formed with an open-sided slot 3, substantially rectangular in cross section, one wall of which is slightly hollowed out to form a shoulder 4. Adapted for loose insertion in the slot is a locking strip 5 substantially square in cross section between which and the base the fabric is received. The fabric is laid over the open side of the slot 3 with its free or short end over the edge adjacent to the hollowed out wall and the main portion on the opposite side, the locking strip being placed squarely thereon and pressed downwards as shown in Fig. 2. This downward movement is continued until the upper corner of the strip on the side adjacent to the hollowed out portion of the

slot can be pushed under the shoulder 4 by 55 tilting the strip as shown in Fig. 1. The fabric is thus gripped between the side walls of the slot 3 and opposite corners of the tilted locking strip 5.

It will be obvious from Fig. 1 that any 60 pull or tension applied to or exerted by the main body of the fabric will tend further to tilt the locking strip and hence increase the gripping action.

In order to assist the tilting action and to 65 retain the locking strip in tilted position when no tension is exerted by the fabric itself, one or more springs 7 is or are fitted to the bottom of the slot near the plane side wall of the slot and are adapted to press 70 upwards upon that corner of the locking strip which is diagonally opposite to the corner engaging the shoulder 4 as clearly illustrated in Fig. 1.

To facilitate tilting of the strip by the 75 fingers or by a tool, when inserting it in place, the strip is preferably rebated as at 8.

I claim:—

1. Fastening means of the type specified, for securing fabric to a rigid base, comprising, in combination, a rigid base having an open-sided slot substantially rectangular in cross section with one side wall plane and the other side wall slightly hollowed out to form a shoulder near the open side of the 85 slot, and a locking strip substantially square in cross section adapted for loose insertion in said slot so as to permit said strip to tilt and wedge the fabric against said shoulder and the plane side wall of the slot, and resilient means to press against the under face of the strip.

2. Fastening means of the type specified for securing fabric to a rigid base comprising, in combination, a rigid base having an 95 open-sided slot substantially rectangular in cross section with one side wall slightly hollowed out to form a shoulder near the open side of the slot, a locking strip substantially square in cross section, and spring means 100 located about diagonally opposite said shoulder and adapted to tilt said strip beneath said shoulder.

3. Fastening means of the type specified for securing fabric to a rigid base comprising, in combination, a base having an open-sided slot substantially rectangular in cross section with one side wall slightly hollowed 105

out to form a shoulder near the open side of the slot, a locking strip substantially square in cross section provided with longitudinal grooves, and spring means located about diagonally opposite said shoulder and adapted to tilt said strip beneath said shoulder.

4. In combination, a base formed with an open sided slot substantially rectangular in cross section and formed in one wall with a recess to provide a limiting shoulder, a strip substantially rectangular in cross section to fit within said slot with the fabric to be held arranged between the strip and walls of the slot, and means arranged in the slot to exert upward pressure on the strip when applied, said strip being tilttable when in proper position in the slot to permit an edge of the strip to engage beneath said shoulder, the diagonally opposite edge of the strip bearing against the wall of the slot opposite the wall formed with the recess, said pres-

sure means serving to hold the strip in locking position in the slot.

5. In combination, a base formed with an open sided substantially rectangular slot, having one wall formed to provide a shoulder adjacent the open side of the slot, a locking strip of substantially rectangular shape with a diagonal length greater than the transverse dimension of the slot, said strip being tilttable following its introduction into the slot to present opposing diagonal edges to engage respectively beneath said shoulder and in contact with the opposite wall of the slot, and resilient means in said slot to hold the strip in tilted position.

In testimony whereof I have signed my name to this specification in the presence of two subscribing witnesses.

DAVID RHYS GRIFFITHS.
